EXTENSIBLE TRESTLE

Bergur L. Brynjolfsson, 4520 N. Clifton Ave.,
Chicago, Ill.

Filed June 29, 1959, Ser. No. 823,609

4 Claims. (Cl. 182—105)

This invention relates to an extensible trestle or adjustable scaffold support and has for its primary object to provide a supporting unit which may be easily adjusted vertically, and including novel clamping units for adjustably clamping an extensible upper section of the trestle to the lower section thereof, and whereby the weight borne by said extensible upper section will urge the clamping units into tight clamping engagement with said upper section for rigidly positioning the upper section relative to the lower section of the trestle.

A further object of the invention is to provide an extensible trestle or scaffold support including clamping units for adjustably securing the extensible upper part of the trestle to the lower part thereof and through which the extensible upper part of the trestle may be readily moved vertically relative to the lower part of the trestle, when no weight is supported thereby.

Various other objects and advantages of the invention will hereinafter become more fully apparent from the following description of the drawings, illustrating a presently preferred embodiment thereof, and wherein:

Figure 1 is a fragmentary side elevational view of the intermediate portion of the trestle;

Figure 2 is an enlarged fragmentary elevational view, partly broken away and partly in vertical section, looking toward the opposite sides of the trestle parts as seen in Figure 1;

Figure 3 is a horizontal sectional view taken through the upper part of the base portion of the trestle, substantially along a plane as indicated by the line 3—3 of Figure 4;

Figure 4 is a fragmentary vertical sectional view taken substantially along a plane as indicated by the line 4—4 of Figure 3;

Figure 5 is a fragmentary transverse vertical sectional view, taken substantially along a plane as indicated by the line 5—5 of Figure 3;

Figure 6 is an enlarged fragmentary vertical sectional view, in detail, taken substantially along a plane as indicated by the line 6—6 of Figure 1, and

Figure 7 is a fragmentary exploded side elevational view of certain of the parts of the extensible trestle.

Referring more specifically to the drawings, the extensible trestle or scaffold support, designated generally 9, includes a base section 10 and an extensible upper section 11. The base section 10 includes two corresponding legs 12 and 13, each of which is composed of a straight ladder having side rails 14 connected by spaced rungs 15. The two ladders or legs 12 and 13 are of the same length and preferably of the same construction. The extensible upper section 11 likewise is composed of a straight ladder having spaced side rails 16 connected by spaced rungs 17. The trestle parts 11, 12 and 13 are conventional and may be of any desired lengths.

The extensible trestle 9 includes two corresponding connecting and clamping units, designated generally 18 and 19, for connecting the ladders or legs 12 and 13 of the base 10 to one another and for adjustably clamping

2

the extensible upper section 11 to said base 10. As the connecting and clamping units 18 and 19 are identical in construction, a description of one will suffice for both.

Each unit 18 and 19 includes a pair of bracket arms 20 and 21 each having an outwardly turned back outer end portion forming an inwardly opening hook or channel 22 of a proper shape and size to fit snugly around three sides of a ladder rail 14. The portion 22 of the arm 20 engages around the upper portion of one of the rails 14 of the ladder or leg 12 and the portion 22 of the bracket arm 21 engages around the upper end of the complementary rail 14 of the other leg or ladder 13. Said portions 22 are secured rigidly to said rails 14 by fastenings 23. The bracket arms 20 and 21 extend inwardly from the inner sides and inner edges of said rails 14 and are disposed crosswise of the ladders 12 and 13 and have overlapping inner free ends 24 and 25, of the bracket arms 20 and 21, respectively, which are provided with registering openings 26. The shank of a bolt and nut fastening 27 extends outwardly through the openings 26 for pivotally connecting the bracket arms 20 and 21 together. It will thus be seen that the fastenings 27 of the two connecting and clamping units 18 and 19 pivotally connect the two ladders or legs 12 and 13 of the base 10 to one another at the upper end of said base and that the axis of the base pivot 27 is disposed between the upper ends of the legs or ladders 12 and 13, as seen in Figures 1, 3 and 5.

Each clamping unit 18 and 19 includes two elongated channel shaped clamping elements 28 and 29 having complementary inner longitudinal edges 30. The clamping element 28 has an apertured ear 31 projecting from its inner edge 30 and the clamping element 29 has a similar apertured ear 32, also projecting from the edge 30 thereof. The ear 31 is outwardly offset slightly, as best seen in Figure 3, for overlying the outer side of the ear 32. The bolt of the fastening 27 of the clamping unit 18 or 19, of which said clamping elements 28 and 29 form a part, extends outwardly through the aligned apertures of the overlapping ears 31 and 32 and thence through the openings 26, and the head of the bolt of said fastening bears against the inner side of the inner ear 32, for pivotally mounting the clamping elements 28 and 29 relative to one another and to the bracket arms 20 and 21. The longitudinal edges 30, which are disposed adjacent the arms 20 and 21, are spaced from one another, above and beneath the ears 31 and 32, when said clamping elements 28 and 29 are disposed substantially parallel to one another, as seen in Figure 5. The clamping elements 28 and 29 have opposite opposed longitudinal edges 33 and 34, respectively, which are likewise spaced from one another when said clamping elements are disposed parallel.

The clamping element 28 has an outwardly turned back extension 35 forming an integral continuation of a part of the edge 33 thereof and which is disposed substantially parallel to the bracket arms 20 and 21. A lever arm 36 is pivotally connected, near one end thereof, to the outer side of the extension 35 by a fastening 37. Said extension 35 and the fastening 37 are disposed substantially below the level of the fastenings 27, as seen in Figures 1 and 2. The clamping element 29 has an outwardly turned back folded extension of its longitudinal edge 34 and which forms an inwardly opening channel 38 which is disposed at an incline relative to the edge 34, so that the upper end thereof is set back from the edge 34 while the lower end thereof protrudes slightly beyond said edge 34, as best seen in Figure 2. Said channel 38 is also disposed near the lower end of the clamping element 29. The intermediate portion of the upper edge of the lever arm 36 is provided with an arcuate notch 39,

and the free end of said arm 36, which is disposed remote from the pivot 37, is inclined slightly as seen at 40 to conformably engage the bed of the channel member 38 when the lever arm 36 is disposed nearly horizontal but inclined upwardly slightly, as seen in Figure 2, from its pivot 37 toward said end 40.

The end 24 of the bracket arm 20 has an extension forming a lug or tongue 41 which projects laterally from a part of the edge thereof above the opening 26. The upper edge of the end 25 of the bracket arm 21 is provided with an elongated arcuate notch 42 which is concentrically disposed relative to the opening 26 of the bracket arm 21 and into which the lug or tongue 41 projects. Said lug or tongue 41 is slidably movable in the notch 42 to allow a limited pivotal movement of the bracket arms 20 and 21 relative to one another. When the legs or ladders 12 and 13 are disposed substantially parallel to one another, as seen in Figure 5, the lug 41 engages one end of the notch 42 to prevent further swinging movement of the lower portions of said legs 12 and 13 toward one another. When the legs or ladders 12 and 13 are fully extended so as to extend downwardly in diverging relation to one another, as seen in Figures 1 and 2, the lug 41 engages the other end of the notch 42 to prevent further swinging movement of the legs away from one another and toward an open position of the base 10.

Since the clamping elements 28 and 29 are pivotally movable on the fastenings 27, relative to one another and to the bracket arms 20 and 21, said clamping elements 28 and 29 may be disposed in upright substantially parallel positions relative to one another, as seen in Figure 5, when the legs or ladders 12 and 13 are spread to fully open positions, as seen in Figures 1 and 2. The side rails 16 of the upper extensible section 11 are spaced apart a distance less than the spacing between the side rails 14 of each of the ladders 12 and 13 and a distance so that one rail 16 can fit in the channels of the clamping elements 28 and 29 of the connecting and clamping unit 18 when the other rail 16 is engaging in the channels of the clamping elements 28 and 29 of the unit 19. With the clamping elements 28 and 29 disposed in substantially upright positions, the edges 33 and 34 of each pair of said clamping elements are disposed sufficiently far apart so that portions of the rungs 17 may pass therebetween. Accordingly, the extensible upper section 11 with its rails 16 engaging the pairs of clamping elements 28 and 29, as previously described, may be slid upwardly therethrough. As each rung 17 passes upwardly between the edges 33 and 34, portions of the rung will engage the bottom edges of the two lever arms 36 to cause the ends 40 thereof to swing upwardly to permit the rung to pass said lever arms. When the upper section 11 has been extended to a desired height, the lever arms 36 can be swung downwardly toward the channels 38 or may swing toward said channels by gravity until the lever arm ends 40 engage in the channels 38. The upper section 11 is then lowered until portions of one of the rungs 17 thereof will come to rest in the notches 39. When this occurs, the weight of the upper section 11 will force the lever arms 36 to swing downwardly toward their positions as seen in Figures 1 and 2. In so moving, the ends 40 of the lever arms by a camming engagement with the beds of the channels 38 will force the clamping elements 28 and 29 to pivot about the fastenings 27 so that the lower ends thereof will swing apart and the upper ends 43 thereof will be swung toward one another and into clamping engagement with the rails 16 above the rungs 17 which engages the notches 39. Engagement of the portions 43 with the rails 16 will prevent the lower portions of the clamping elements 28 and 29 from swinging further apart than as shown in Figures 1 and 2, and in which position the lever arm ends 40 are wedged in the channels 38 and are prevented from swinging downwardly past the position

of the lever arm 36 as seen in Figure 2. The weight of the upper trestle section 11 and the platform or other load supported thereby, not shown, will effectively maintain the pairs of clamping elements 28 and 29 in tight clamping engagement with the rails 16 and will also maintain one of the ladder rungs 17 securely seated in the notches 39 for supporting the upper section 11 rigidly with respect to the base 10.

The clamping elements 28 and 29 have been illustrated of arcuate cross section to conform to the circular or tubular shape of the rails 16; however, said elements 28 and 29 could be of other cross sectional shape to conformably engage rails of other cross sectional shapes.

Various modifications and changes are contemplated 15 and may be resorted to, without departing from the function or scope of the invention as hereinafter defined by the appended claims.

I claim as my invention:

1. An extensible trestle comprising, in combination 20 with a pair of ladders disposed in downwardly diverging relation to one another and forming a trestle base and a ladder extending upwardly from the base and forming an extensible upper section of the trestle; connecting and clamping units hingedly connecting the upper ends of 25 the base ladders to one another and adjustably supporting the extensible section ladder therebetween, each of said units including a pair of bracket arms rigidly secured to and extending inwardly from complementary rails of the two base ladders and having overlapping inner 30 ends disposed between said rails, a fastening extending loosely through said overlapping inner ends and pivotally connecting said rails of the two ladders to one another between the ladders, each of said units including a pair of elongated clamping elements of channel shaped cross 35 section having complementary longitudinal edges provided with overlapping extensions through which said fastening loosely extends for pivotally mounting said clamping elements on inner sides of the bracket arms, said fastenings being spaced from upper and lower ends 40 of said clamping elements, the clamping elements of said two units being disposed between the bracket arms thereof, the rails of the ladder of the extensible upper section fitting slidably in said pairs of clamping elements, the other inner longitudinal edges of the clamping elements 45 of each pair being spaced apart a distance sufficient to permit the rungs of said upper extensible ladder to slide freely therebetween for extending or retracting said upper section vertically relative to the trestle base, and means for closing the gap between said inner edges of said 50 clamping elements, beneath the fastening thereof, to provide a support for one of the rungs of the extensible upper ladder and for camming the lower portions of said clamping elements away from one another to swing the upper ends of said clamping elements into clamping 55 engagement with the ladder rail of the extensible ladder for rigidly supporting said extensible ladder relative to the trestle base.

2. An extensible trestle as in claim 1, said closing means comprising a bar pivotally connected to the outer 60 side of one of the clamping elements near the inner longitudinal edge thereof and forming a lever arm, said other clamping element having a rigid channel portion disposed on the outer side thereof and opening toward the arm pivot, said channel portion being disposed at an incline downwardly toward said inner longitudinal edge of the last mentioned clamping element to combine with the free end of the arm to form the cam means and whereby said free end of the arm is wedged in said channel portion, against downward swinging movement when the upper ends of the clamping elements are swung inwardly into clamping engagement with the ladder rail.

3. An extensible trestle as in claim 2, said arm having an upper edge provided with a notch in which a part 65 of the rung, engaged by the arm, seats, said notch co-

operating with the upper ends of the clamping elements to retain the upper trestle section immovable relative to the trestle base.

4. An extensible trestle as in claim 1, and means interconnecting the bracket arms of each of the connecting and clamping units for limiting pivotal movement of said bracket arms relative to one another for limiting swinging movement of the ladders of the trestle base toward open extended positions.
